WINCH CONSTRUCTION

Charles B. Curtiss, Bay City, Mich.

Application July 11, 1940, Serial No. 344,831

4 Claims. (Cl. 242—117)

This invention relates to improvements in winch construction, and more particularly to a welded winch structure adaptable for mounting on automotive trucks and the like.

One of the prime objects of the invention is to design a winch structure of simple and practical construction which will be light in weight, of maximum strength, which can be easily and economically manufactured and assembled, and which will not suddenly rupture even when excessively loaded.

Another object is to design a winch structure made up of plate and structural members, which can be readily fabricated and welded with a minimum of labor and equipment.

A further object is to design a fabricated drum made up of differing classes of stock materials, and provide tubular end extensions so mounted and welded in position as to maintain the several parts in true and exact alignment.

A still further object is to provide a winch having welded plate bearing supports that require a minimum of machining, and which can be readily assembled and welded in position.

A further object still is to provide a winch having a simple and inexpensive worm case and a worm wheel center formed of inexpensive materials where stresses are light, and of strong, heat treated alloy materials only in such places as are subjected to excessive strains, said case and worm wheel center being composed of few parts, which can be readily assembled in a fixture, and which also requires a minimum of machining.

With the above and other objects in view, the present invention consists in the combination and arrangement of parts, hereinafter more fully described, illustrated in the accompanying drawings, and more particularly pointed out in the appended claims, it being understood that changes may be made in the form, size, proportions and minor details of construction, without departing from the spirit, or sacrificing any of the advantages of the invention.

In the drawings:

Fig. 1 is a side, elevational, part sectional view showing my improved winch construction.

Fig. 2 is a longitudinal, sectional view showing the drum and end extensions in assembled relation.

Fig. 3 is an end view thereof.

Fig. 4 is an end elevational view of the assembled winch.

Fig. 5 is a detailed, side elevational view of the main frame.

Fig. 6 is an end view thereof.

Fig. 7 is a sectional, elevational view through one of the bearing supports.

Fig. 8 is an end elevational view thereof.

Fig. 9 is a part sectional, side elevational view of the worm wheel center.

Fig. 10 is an end elevational view thereof.

Fig. 11 is an enlarged view showing the manner of connecting the worm wheel center and the shaft.

Where winches are mounted on motor trucks and on moving structures, many problems not present in a rigid, stationary, mounting are encountered. For example, when the motor truck

5 is on an uneven footing, there is the possibility of the weaving of the chassis causing twisting of the winch structure. Furthermore, excess driving power is always available and operators are oftentimes tempted, depending on circumstances 10 and conditions, to handle unreasonable overloads. Other operators sometimes make short pulls off the side of the motor vehicle, setting up excessive end thrust on the drum, and it is therefore advantageous and desirable to design a welded 15 winch structure which will have maximum strength, which will be light in weight, and which will have excess strength in all parts supporting the rope load, thus preventing complete failure as is apt to occur when the rope loads are supported by main parts formed of cast materials.

20 The general operation of the winch is substantially the same as described in Patent No. 1,952,658, granted to me March 27, 1934, the present application being directed to a welded construction 25 which makes possible a winch of high quality and maximum strength at minimum cost.

The winch as shown in the attached drawings 30 is designed for motor truck mounting and consists of a base B, a welded drum assembly C, and a worm case assembly D, said base comprising a pair of spaced apart angles 12 connected by plates 13 which span said angles and are welded thereto. End frames E are welded to these angles 12 in alignment with the plates 13, and comprise web 35 plates and gussets 14 and 15 respectively, which form the end supports for the drum assembly C, which gussets and end supports make angle and T-sections to carry the drum load down to the base angles 12.

40 45 50 Steel plate bearing supports 16 are bolted to the end frames E by means of bolt 17 and are designed to pillow bronze spherical drum supporting bushings 18 which are mounted in a poured metal bearing 19. These spherical bushings compensate for any weave in the vehicle

chassis (not shown) and prevent binding, and it will be obvious that all operating wear will come on the cylindrical bore of the bushings 18, said bushings being held against rotation by the dowel 20 which also serves to carry lubrication thereto.

The drum assembly C is made up of a piece of stock pipe 21 with a spaced apart flange and brake drum 22 and 23 respectively, welded thereon to form the winding drum, the flange 22 being formed of flat plate with gussets 24 welded thereto to oppose end thrusts, and a protecting flange 25 is welded to the brake drum to prevent damage to the brake drum, an opening 26 being provided in the web of said brake drum and in the flange to facilitate anchoring of the hoist rope or cable 27 as usual.

End extensions F are provided in the opposite ends of the drum pipe 21, each extension comprising a heat treated alloy steel tube 28 having a relatively short tube 29 welded thereon at a point where the annealing of the heat treated alloy steel tube by the weld will not result in lessened winch strength. A flat disc or flange 30 is welded on said tube 29, and a flange 31 is welded on the inner end of the tube 28. The assembled extensions are then welded, by jig, into the drum pipe 21, openings 32 being provided in the drum 21 in circumferential alignment with the flange 31 to facilitate welding the extension in position, and the disc 30 is welded to the end of the drum pipe 21 so that a rigid structure is secured. These discs 30 and 31 stiffen and reinforce the pipe against any possibility of collapse, provide proper support for the end extensions, and also carry the torque from the worm wheel clutch to the drum.

A bushing 33 is provided adjacent the outer end of the splined extension, and a shaft 34 is journaled therein in the usual manner.

The worm case 35 is also of all-welded construction to give maximum strength with least weight, the outer shell is of rolled and formed plate, and the bottom 36 is of the same material bent in the shape of a wide U. A plate 37 forms one side wall of the worm case and is provided with a centrally disposed opening 38 in which a short tube 39 is welded, and ribs 40 are welded to the inner face of the plate 37 to reinforce and take the side load of the worm wheel.

Horizontally aligned openings 41 are provided in the lower end of the case, and tubular sections 42 are inserted in said openings and are welded in position in the usual manner, these sections serving to support the raceways of bearings 43 in which the worm 44 is journaled. These tubular sections 42, together with the shell 35, the bottom 36, and the torque bar support lugs 45, are all welded together in a locating fixture.

The worm wheel center W comprises a sleeve 46 which slides over the end of the shaft 34, the web 47 of the worm wheel being welded on said sleeve, and a cylindrical section 48 is welded thereto to centering the bronze rim of the toothed section 49 of the worm wheel, and bolts 50 serve to secure this toothed section to the web, a plate 51 forming a closure for the open end of the cylindrical section which is also welded to the sleeve.

This worm wheel assembly is inserted through the opening 52 provided in the outer end wall of the worm case, and a cover 53 forms a closure for said opening, this cover being formed similar to the end wall 37 and having a centrally disposed tube 54 welded therein, together with radiating ribs 55 welded to the inner face thereof, said

cover being secured in position by means of bolts 56 in the conventional manner.

The ends of the sleeve 46 are splined as at 57 as is also the end 58 of one of the end extensions 5 28, and a longitudinally shifttable broached clutch ring 59 is provided for engaging or disengaging the members 23 and 46, spaced rings 60 being welded on the clutch ring 59, and between which a shifting fork 61 acts and it will be obvious that 10 the clutch ring 59 can be shifted to position to drivingly engage the worm wheel center and drum, or to disengage the worm wheel from the drum. Short steel bushings 62 are provided in the sleeve 46 of the worm wheel center to center 15 the main shaft 34 and to line the two splines.

The ends of the shaft 34 are splined as at 64 and a short broached and splined spacer ring 65 fits thereon, the inside diameter being broached to fit the shaft 54, the outer periphery of said ring 20 being splined as at 66, and a broached ring 67 fits over and drivingly connects the splined ring 66 and the splined end of the worm wheel center for driving the shaft 34 and the niggerhead 68 which is mounted on the opposite end thereof, a disc 69 being secured to the end of the shaft 34 to limit endwise movement thereof.

The niggerhead 68 is also an all-welded construction and is mounted on the opposite extension tube 28, a short, broached, and splined spacer ring 70 being mounted on the splined end of the shaft 34, the outer periphery of said ring being splined as at 71 and engages the broached end 72 of the niggerhead 68 so that the niggerhead is driven when the worm wheel is actuated.

A brake band 73 is provided on the brake drum 25 as usual, and suitable means (not shown) are provided for the operation thereof.

A sprocket 74 is mounted on the end of the worm shaft 44 and is driven from a power take-off on the vehicle (not shown), or from any other convenient source of power.

From the foregoing description, it will be obvious that I have perfected a very simple, and substantial, all-welded winch, which can be easily 45 and economically manufactured and assembled, and which combines high quality and high strength at low cost.

What I claim is:

1. In a winch drum, a tubular body; end flanges 50 welded on the exterior of said body adjacent to the ends of the latter; reinforcing webs welded on said flanges and on said body and extending in the direction of the longitudinal length thereof between the ends of said body and the flanges; 55 shaft-receiving tubular extensions extending into the ends of said body and arranged axially of the latter; and means securing the extensions on the interior of said body for accurately centering and rigidly fixing the extensions to the body and for reinforcing the latter adjacent to the flanges.

2. In a winch drum, a tubular body; end flanges 65 welded on the exterior of said body adjacent to the ends of the latter; reinforcing webs welded on said flanges and on said body and extending in the direction of the longitudinal length thereof between the ends of said body and the flanges; shaft-receiving tubular extensions extending into the ends of said body and arranged axially of the latter; and spaced disks welded on each extension 70 and on the interior of said body for rigidly fixing the extensions to the body.

3. In a winch drum, a tubular body; end flanges 75 welded on the exterior of said body adjacent to the ends of the latter; reinforcing webs welded on said flanges and on said body and extending

in the direction of the longitudinal length thereof between the ends of said body and the flanges; shaft-receiving tubular extensions extending into the ends of said body and arranged axially of the latter; and spaced disks welded on said extensions and on the interior of said body for rigidly fixing the extensions to the body and for reinforcing the latter, said body having openings in alignment with the disks for the admission of welding flux for adherence to the body and the 10 disks.

4. A winch drum formed of a plurality of

welded units, the main body comprising a standard pipe having end flanges welded thereon adjacent to and spaced from the ends of the pipe to form a winding drum, a brake drum welded 5 on one of said flanges, an individual shaft-receiving end assembly mounted in each end of the pipe, each assembly comprising a tubular section having spaced apart disks welded thereon and on the body, with one end of each tubular section projecting beyond the end of said pipe.

CHARLES B. CURTISS.
